UNITED STATES PATENT OFFICE.

JACQUES M. VAN DEN BERGHE, OF MONTREAL, QUEBEC, CANADA.

FIRE-DOOR FOR FURNACES AND THE LIKE.

1,132,064.

Specification of Letters Patent. Patented Mar. 16, 1915.

Application filed June 15, 1914. Serial No. 845,044.

To all whom it may concern:

Be it known that I, JACQUES M. VAN DEN BERGHE, a subject of the King of Belgium, residing at No. 615 Mount Royal avenue 5 east, Montreal, Province of Quebec, Canada, have invented certain new and useful Improvements in Fire-Doors for Furnaces and the like; and I do hereby declare that the following is a full, clear, and exact description of the invention, such as will enable others skilled in the art to which it appertains to make and use the same.

The invention to be hereinafter described relates to fire doors for furnaces and the like.

In order to more clearly disclose the construction, operation, and use of the invention, reference should be had to the accompanying drawings forming part of the present application. Throughout the several figures of the drawings like reference characters designate the same parts.

In the drawings: Figure 1 is a front view of the door; Fig. 2 is a left side view of the same; Fig. 3 is a section on line 3—3 of Fig. 1 looking in the direction of the arrows; Fig. 4 is a side view of the cylinder valve; and Fig. 5 is a section on line 5—5 of Fig. 4 looking in the direction of the arrows.

The main objects of the invention are, to provide a neat, compact, durable, and efficient door for furnaces and the like, which can be operated manually by steam taken directly from the engine boiler, or by any other fluid pressure, as desired. This door is specially intended for use with furnaces used in connection with engine boilers, and for similar purposes. Referring to the drawings in detail, 1 designates the side beams of the door which are grooved longitudinally to receive slidably mounted racks 2. The racks 2 are provided, at their upper ends, with inwardly directed integral pintles 3 which project through slots 2a in the inner faces of beams 1 and carry the upper leaf 4 of the door, which is slidably mounted between side beams 1. The lower leaf 5 of the door is secured along its lower edge, to a transverse bar 6 rotated in bearings 7 secured to the side beams of the door, at the outer edge and near the bottom there-

of. A segmental gear 8 is keyed on rod 6, near each end thereof and in mesh with rack 2. By this construction, when bar 6 is given a half rotation, the lower leaf 5 of the door is turned outwardly and downwardly, to a vertical position, the reverse of its original position, as indicated in Fig. 3. At the same time, gears 8 engage with racks 2 and force them upwardly thus raising the leaf 4 of the door to the position indicated by dotted lines in Fig. 1. This leaves the doorway open to its fullest extent and so places the leaves of the door as not to interfere in any way with the coaling of the fire.

On one end of rod 6 a gear 9 is keyed in mesh with a segmental gear 10 rotatably mounted on the side of the door frame. Gear 10 is normally held in lowered position by a tension spring 11 which has its upper end secured thereto and its lower end secured to the beam, mounted in a suitable groove in the outer face of the said beam. A pitman 12 has its lower end pivotally connected to gear 10, at the center of its arc, and its upper end pivotally secured in a block 13 which is slidably operative in a guide bracket 14 secured to the outer face of side beam 1, and is integral with the lower end of a piston rod 15. Piston rod 15 is connected to a piston 16 operative in a cylinder 17 secured to the outer face of the said frame, above bracket 14. For the purpose of raising piston 16 a specially constructed valve is arranged at the lower end of cylinder 17, at one side thereof and communicating therewith.

The valve 18, which is of cylindrical shape and adapted to fit the interior of valve casing 19 snugly, is provided with an L bore 20 the inner end of the stem of which matches with the outer end of a bore 21 extending through the side of the cylinder. The stem 22 of the valve projects through the center of the side of the casing 19, and has its outer portion squared to fit the square eye 23 on the lower end of a short arm 24 which is secured thereon, by means of a pin passed through the eye and the valve stem, or by other suitable means. The upper end of arm 24 is pivotally connected

to the upper end of an arm 25, the lower end of which is pivotally connected to the outer end of a rocking beam 26 pivotally mounted in a lug 27 integral with bracket 14. The inner end of the beam 26 is pivotally connected to the upper end of an arm 28 the lower end of which is pivotally connected to the inner end of a foot lever 29 pivotally mounted in a bracket 30 secured to the side of the door frame. The inner end of beam 26 is normally held depressed by a tension spring 34 secured thereto and to the door casing.

A pipe 31 leads directly from the dome of the engine boiler to the center of the front face of valve casing 19 and is provided with a control valve 32 which is normally kept open. A blow off 33 is connected to the center of the under face of the valve casing. Normally, valve 18 is in such a position that the outer end of the arm of the L bore 20 is matched with the inner end of the blow off 33, as in Fig. 5. This effectually closes the ends of pipe 31 and prevents any steam from entering cylinder 17. When it is desired to open the door, the outer end of lever 29 is depressed. This acts, through arms 24, 25, and 28, and beam 26 to rotate valve 18 in the direction of the arrow, in Fig. 4, so as to match the outer end of the arm of bore 20 with the inner end of pipe 31. The steam, which is under pressure, flows through bores 20 and 21 into the cylinder 17, so as to force the piston 16 up. As the piston rises the piston rod 15 also rises and acts through pitman 12 to rotate the segmental gear 10, which meshes with gear 9 keyed on the end of rod 6, and rotate the rod. As rod 6 rotates, it acts to open the door, as previously described.

When the outer end of lever 29 is released, spring 34 acts, through beam 26 and arms 25 and 24, to return valve 18 to its initial position, which permits the steam to escape from cylinder 17 through blow off 33, as in Fig. 5. As soon as the steam starts to escape from cylinder 17, spring 11 acts to rotate gear 10 back to its initial position and closes the door.

If, for any reason, it is not desired to operate the door by steam pressure, it may be connected so as to be operated directly from the foot lever. In this case, the upper end of pitman 12 is disconnected from block 13 and is connected to the inner end of lever 29, from which the lower end of arm 28 has been previously disconnected. By this connection, depressing the outer end of lever 29, will act directly through pitman 12 to rotate gear 10 and open the door.

This door is quickly and easily operated and need not be open during the whole time required for cooling, or other purposes, but is only open momentarily. This results in

the saving of a great deal of heat, as well as sparing the operator the ordeal of being needlessly exposed to the intense heat for a considerable length of time.

To insure accuracy of operation and prevent possible damage, due to opening the door too wide or closing it too tightly, the segmental racks 8 have their arcs completed by a plain segment so as to form a full circle, and have their arcs of such length as to move the racks 2, or permit movement thereof, for a predetermined distance only. As soon as the end of the arc of the gear is reached, the end of the plain segment engages the teeth of the rack and effectually prevents further movement thereof, as well as preventing any further movement of gears 8 and rod 6.

Plates 35 are secured to the side beams 1, at the top thereof, so as to extend inwardly beyond the inner sides thereof and form, with the extended inner portion of the side beams, a suitable groove or track for the travel of the upper leaf 4 of the door.

It is thought that the construction, operation, and use of the invention will be clear from the preceding detailed description.

Changes may be made in the construction, arrangement, and disposition of the several parts of the invention without in any way departing from the field and scope of the same, and it is meant to include all such within this application wherein only a preferred form has been disclosed.

Having thus fully described my invention, what I claim as new and desire to secure by Letters Patent is:

1. In a door of the character described, grooved side beams, racks slidably mounted in the grooves thereof, a slideable door leaf carried thereby, a transverse bar rotatably mounted on the side beams, a door leaf secured thereto along its lower edge, segmental gears keyed on the said bar in mesh with the said racks, a gear keyed on one end of the said bar, a rotatable segmental gear in mesh therewith, a piston rod, means for raising the said piston rod, and connections between the said segmental gear and piston rod whereby the gear is rotated when the piston rod is raised.

2. In a door of the character described, grooved side beams, racks slidably mounted in the grooves thereof, a slideable door leaf carried thereby, a transverse bar rotatably mounted on the said side beams, segmental gears keyed thereon and in mesh with the said racks, a gear keyed on one end of the said bar, a rotatably mounted segmental gear in mesh therewith, a cylinder, a piston mounted therein, means for admitting fluid under pressure into the cylinder under the piston, a piston rod carried by the said piston, connections between the said segmental

gear and piston rod whereby the gear is rotated when the piston rod is raised, means for permitting the escape of the fluid from the cylinder, and means for returning the 5 said segmental rack to its initial position, when the said escape means is opened.

In witness whereof I have hereunto set my hand in the presence of two witnesses.

JACQUES M. VAN DEN BERGHE.
